UNITED STATES PATENT OFFICE.

CHARLES GLEE, OF WHITE, NEBRASKA.

ROAD DRAG.

Application filed October 26, 1923. Serial No. 670,920.

To all whom it may concern:

Be it known that I, CHARLES GLEE, a citizen of the United States, residing at White, in the State of Nebraska, have invented certain new and useful Improvements in Road Drags, of which the following is a specification.

This invention relates to improvements in road drags for scraping or leveling roads and highways and has for its object to provide a device of this character which can be adjusted to work at various depths, the adjusting means being yieldable to successfully withstand the strain incident to working or grading rough roads.

A further and additional object of the invention is to provide a road scraper of simple and economic construction embodying comparatively but a small number of parts which can be readily and conveniently assembled into a working structure.

Various other objects and advantages of the invention will become apparent from the following disclosure wherein:

25 Figure 1 is a top plan view of the proposed scraper,

Figure 2 is a view in side elevation thereof,

30 Figure 3 is a sectional view along line 3—3 of Figure 1, and

Figure 4 is a detail section along line 4—4 of Figure 1.

The frame of the scraper is constructed of a pair of side beams 10 and 11 connected together at one end, as indicated at 12, to provide a V-shaped frame as illustrated. Beam 10 constitutes the land-side of the frame and is provided with a land-side wheel 13 mounted on a shaft 14 suitably journaled in a boxing 15 at the rear end of the beam.

40 The wheel is located on the inside of the beam which is provided with a substantially heavy strap iron 16 for supporting the inner end of the shaft as illustrated. The opposite beam 11 of the frame constitutes the scraper side and is provided along its lower edge with a scraper blade 17. To beam 11 is also attached the draft rigging 18, the same being connected by a clevis 19 to a pull chain 20. One end of the chain being connected

50 to a clamp 21 which is fastened about the beam as shown. The opposite end of the chain connects with a rod 22 which is likewise provided with a clamp 23, the latter being secured adjacent the rear end of beam 11.

The driver's seat 24 of the scraper is suit-

ably mounted on a platform of planking 25 extending between the supporting sills 26 and 27 which extend crosswise between beams 10 and 11 at a point preferably nearer the rear end of the machine than the forward end thereof.

In use, the scraper is dragged over the surface of the road or highway to be leveled and the dirt thereof is scraped up and distributed by blade 17 and beam 11, the latter extending at an incline across the road as will be readily understood. The depth of the cut may be regulated from the driver's seat 24 thru the instrumentality of the lever 28. As shown in Figure 1, this lever is rigidly connected with one end of a crank shaft, 29 suitably journaled in bearings 30 and 31, the former being located on beam 11 and the latter being mounted on a cross sill 32 extending between sills 26 and 27. The crank 33 of the shaft operates in a block 34 of a slot 35 carried at one end of a rocker arm 36. Arm 36 turns on a pivot pin 37 carried by the bracket 38 which is on sill 27. At its outer end arm 36 supports a ground engaging wheel 39 mounted to turn on a swivel 40 so as to readily follow the movement of the frame in any direction. When crank 33 is turned to move the block 35 end of arm 36 upwardly, wheel 39 will be brought into engagement with the ground surface and will tend to lift beam 11 as the crank continues on its upward movement. Similarly, when the crank moves downwardly, arm 36 will be rocked on its pivot to elevate wheel 39, the weight of the frame causing blade 17 to penetrate the surface of the road deeper and deeper as the outer end of the arm becomes elevated. The turning of the crank shaft is accomplished by means of lever 28 and in order that the same may be held stationary in any position for locking the rocker arm, a brake ratchet 41 is loosely mounted on shaft 29 for engagement with the pawl 42 of the brake lever. On the inside of the brake ratchet and adjacent each end thereof is provided an outstanding lug 43. These lugs are adapted to alternately come to rest upon a flat arched spring 44 extending longitudinally of sill 32 to which it is secured as indicated at 45. This spring provides a yieldable rest for the brake ratchet when it is located on either the right or left side of the crank shaft and tends to absorb the shock imparted to the locked brake lever when the ground engaging wheel 39 engages

ruts, rocks or other obstructions in a road. In the position of the parts illustrated in Figure 3 it will be obvious that any upward movement of wheel 39 will cause block 35 to impart a downward thrust on crank 33 of the shaft thereby tending to force the locked lever and ratchet in a downward direction. The downward thrust of the lever and ratchet is yieldably resisted, in the present invention, by springs 44 against which rests the lug 43 of the ratchet. Being elastic, the spring is flexed slightly under the strain imparted thereto and, hence, serves to cushion the parts so as to prevent breakage or snapping off thereof under sudden or heavy strain and stresses.

From the foregoing it is thought that the advantages and novel features of the invention can be readily understood and that further detail description thereof is not required.

What is claimed is:

1. A road drag comprising a scraper frame, a rocker arm associated therewith, a ground engaging wheel at one end of the said arm, an operating crank engaging the opposite end of the arm for rocking the latter on its fulcrum, means for locking the crank in adjusted position and cushioning means for the said lock of the crank whereby the latter will be cushioned against the shock imparted thereto.

2. A road drag comprising a scraper frame, a ground engaging wheel, a rocker arm associated with said frame and supporting the said ground engaging wheel, a crank shaft having engagement with the said arm for rocking the same on its fulcrum, an op-

erating lever fixed on said shaft, and carrying a locking pawl, a brake ratchet loosely mounted on said shaft and having engagement with the said pawl, and a flat spring adapted to provide a yieldable rest for the said ratchet when disposed at rest on either side of the said shaft, said ratchet and spring serving to yieldably support the said lever in its locked position whereby it is cushioned against shocks and strains imparted thereto.

3. A road drag comprising a scraper frame of V-shaped formation, one side of said frame constituting a land-side and the other side constituting a scraper, a driver's seat supported crosswise of the frame, a rocker arm arranged adjacent the rear end of the scraper side of the frame and having a ground engaging wheel at its outer end, a crank shaft journaled in the frame and operating in a slot at the inner end of the said rocker arm, an operating lever fixed on said shaft at one end and provided with a locking pawl, an arched spring associated with the said frame adjacent the said lever, and a brake ratchet loosely mounted on said shaft to be engaged by the locking pawl of the said lever, said ratchet having a lug outstanding from opposite ends thereof and adapted to rest upon the said spring when the ratchet is disposed on either side of the said shaft whereby it yieldably supports the lever locked thereto, said ratchet and yieldable spring serving to cushion the lock lever against shock and stresses imparted thereto.

In testimony whereof I affix my signature.

CHARLES GLEE.
